UNITED STATES PATENT OFFICE.

AARON LEVINGSTON, OF KANSAS CITY, MISSOURI.

PEN OR PENCIL POINT PROTECTOR.

No. 866,148.

Specification of Letters Patent.

Patented Sept. 17, 1907.

Application filed April 2, 1907. Serial No. 366,057.

To all whom it may concern:

Be it known that I, AARON LEVINGSTON, a citizen of the United States, residing at Kansas City, in the county of Jackson and State of Missouri, have invented 5 certain new and useful Improvements in Pen or Pencil Point Protectors, of which the following is a specification.

This invention relates to pen or pencil point protector and my object is to produce a simple device of 10 this character which will cover or expose the point of the pen or pencil with which it is equipped.

A further object is to produce a device of this character which is of simple, strong, durable and cheap construction.

With these objects in view the invention consists in certain novel and peculiar features of construction and organization as hereinafter described and claimed; and in order that it may be fully understood, reference is to be had to the accompanying drawings, in which—

20 Figure 1, is an elevation of a pencil equipped with a protector embodying my invention. Fig. 2, is a similar view with the reciprocatory element of the protector covering the point of the pencil. Fig. 3, is a central, vertical, longitudinal section of the pencil and the 25 protector. Fig. 4, is a detail perspective view of the clamp element of the protector.

Referring to the drawings in detail, 1 indicates a cylindrical sleeve of spring metal having a truncated conical front end 2 and provided with longitudinal 30 slits 3 in its rear end, said slits forming between them tongues 4. The sleeve is also slotted longitudinally at 5 for nearly its full length to produce a long tongue 6, the rear ends of all the tongues being preferably bowed inward to produce clamping jaws 7. The long tongue 35 is also formed externally at a suitable point with an outwardly projecting boss 8, which boss can be disposed inward of the internal diameter of the sleeve by pressing inward on the tongue 6.

9 indicates a sleeve adapted to fit telescoped upon 40 sleeve 1 and provided with a truncated conical front end 10 and with a longitudinal slot 11, the latter being adapted to receive the boss 8 of sleeve 1 after the sleeve 9 has been slid upon sleeve 1 until the slot is disposed opposite said boss, it being understood that the tongue 45 6 is pressed inward while the above adjustment takes place and when released springs outward and disposes said boss in the slot, it being noticed in this connection that the ends of the slot are preferably enlarged as at 12, for a purpose which hereinafter appears, and for 50 convenience in sliding sleeve 9 forward or rearward

upon sleeve 1; the former is provided with beads or collars 13.

In practice the protector with the parts assembled as explained, is slipped upon the pencil or any equivalent device until the truncated end 2 of sleeve 1 is arrested by engagement with the sharpened or tapered end of the pencil or other device, the bowed ends 7 of the tongues pressing firmly against the pencil or other device and preventing accidental movement of sleeve 1 thereon. If it be desired to use the pencil 80 the outer sleeve 9 is slid from the position shown in Figs. 2 and 3 to the position shown in Fig. 1, such movement being arrested preferably by the engagement of boss 8 with the front end of slot 11. If it is not desired to use the pencil the sleeve is left in the position shown in Figs. 2 and 3 so as to protect the point of the pencil from breakage or from catching upon and injuring the apparel of the person in whose pocket it may rest.

In the actual device the boss is preferably formed by 70 punching a hole outwardly through sleeve 1, this method producing a boss which tapers outward and which under the resiliency of tongue 6 will be disposed with its base portion or portion of greatest diameter, in either of the enlargements 12 and thus guard 75 against accidental downward or rearward slippage of sleeve 9 on sleeve 1 or against opposite slippage in case the pencil is held in an inverted position or with the point downward. In view of this construction it will be apparent that when the sleeve 9 is grasped and 80 pushed in either direction upon sleeve 1 the tapered boss 8 will be pressed inward so that its smaller outer portion will travel in the slot, the resiliency of the tongue reprojecting the boss outward into the opposite enlarged end of the slot when such end is reached. It 85 will thus be seen that it will require a positive application of endwise pressure on sleeve 9 to move it from either of its extreme positions of adjustment and consequently that the pencil point cannot be accidentally exposed or covered.

It will also be noticed that as the protector is of but little greater diameter than the pencil and has no material projections externally it need not be removed while the pencil or pen is in use, being removed of course while the pencil is being sharpened or the pen 95 point, as the case may be, is being replaced.

From the above description it will be apparent that I have produced a pen or pencil point protector possessing the features of advantage enumerated as desirable and I wish it to be understood that I do not desire to be 100

restricted to the exact details of construction shown and described as obvious modifications will suggest themselves to one skilled in the art.

Having thus described the invention, what I claim 5 as new and desire to secure by Letters Patent, is:—

A pen or pencil point protector comprising a spring sleeve having a truncated conical front end and provided at its rear end with a plurality of spring tongues bowed inwardly to yieldingly engage the pencil or penholder and 10 hold the sleeve thereon, the sleeve being provided between its ends with an outwardly projecting boss, and a slideable sleeve having a truncated front end and fitting snugly on

the spring sleeve and having a longitudinal slot engaged by the boss on the spring sleeve to guide its movement and further provided at the ends of said slot with enlargements to be automatically engaged by said boss whereby the movement of the slideable sleeve will be arrested and the said sleeve held in its adjusted position.

In testimony whereof I affix my signature, in the presence of two witnesses.

AARON LEVINGSTON.
